UNITED STATES PATENT OFFICE

FRANK B. DICKASON, OF SHREVEPORT, LOUISIANA

GARAGE, BARN, AND WAREHOUSE DOOR

Application filed May 9, 1930. Serial No. 451,078.

This invention relates to certain new and useful improvements in doors and supports therefor.

One of the principal objects of the invention 5 contemplates the provision and arrangement of a mounting for the door whereby the latter may be disposed in vertical and horizontal planes.

Another object of the invention consists of 10 weight operated means normally holding the door in open position.

A further object of the invention embodies a latch mechanism for the door operable from both sides.

15 More specifically stated the door construction is to be provided with jambs upon both sides of the door to facilitate alignment of the latch mechanism.

With the above and other objects in view, 20 the invention further consists of the following novel features and details of construction, to be hereinafter more fully described, illustrated in the accompanying drawings and pointed out in the appended claim.

25 In the drawings;

Figure 1 is a rear elevation of the improved form of door construction and operating mechanism therefor.

Figure 2 is a vertical sectional view taken 30 through the door frame with the door disposed in closed position.

Figure 3 is a view similar to Figure 2 illustrating by full and dotted lines the relative positions of the door when shifted to 35 occupy its respective positions.

Figure 4 is a vertical sectional view taken on line 4-4 of Figure 1.

Figure 5 is an enlarged fragmentary front elevation of an appropriate portion of the 40 door and latch operating mechanism.

Figure 6 is a fragmentary rear elevation of the door and jamb therefor.

Figure 7 is a horizontal sectional view taken on line 7-7 of Figure 1.

45 Figure 8 is a view similar to Figure 7 taken on line 8-8 of Figure 1.

Figure 9 is a fragmentary perspective view of a post of the door frame illustrating the arrangement of the battens, stops, jambs, 50 guides, etc.

Referring to the drawings in detail where-in like characters of reference denote corresponding parts, the reference character 10 indicates a door frame having vertically arranged slots or passageways 11 upon diametrically opposite sides thereof, to facilitate accommodation of the projecting extremities of a fulcrum bar 2. The latter being carried by the form of door or closure, such as indicated at 13, in the manner suggested in Figures 1, 2, 3 and 4. Said door is of box like construction, that is, the side, top and bottom rails project rearwardly for appreciable distances beyond the inner side of the facing for the door. A multiplicity of 55 cross braces, such as indicated at 14 are joined at their ends and at intervals to the adjacent portions of the door side rails. From the foregoing it will be understood that the form of door may be shifted to occupy the positions shown in Figures 2 and 3 of the drawings.

Bracket arms 15, carried by and rearwardly projected from the door frame 10, are provided with aligned vertical slots 16 accommodating the ends of a beam or rod 17 for rocking motion therein. Leg members, such as indicated at 18, carried by and depending from the rod or beam 17 subsequently terminate to provide inwardly offset pintles 19 70 journaled at 20 in the door 13.

Pulley wheels or sheaves 21 journaled upon the brackets 15 have passed thereover flexible connectors 22 which have connection at their ends with the outwardly projecting extremities of the fulcrum bar 12 within the boxings of the door frame and weight members 23; the latter being sufficient in avoirdupois to overbalance the weight of the door 13 whereby the latter will be normally induced to occupy the position shown in Figure 3 of the drawings.

As will be understood from the illustrations of my invention in Figures 7 and 8 of the drawings, the upper and lower halves of the door are provided with separate jambs disposed upon opposite sides thereof. The upper portion of the door is provided with jamb portions 24 formed as continuations of the outer sides of the door for abutting en-

gagement with the door frame 10. As mentioned in the foregoing, the fulcrum bar 12 is slidably mounted within the slots 11 and which are formed between the adjacent sides 5 of the frame 10 and strip members 25. Spacing members 26 carried upon the inner portions of the door frame and aligned with the inner side of the door opening are secured to the lowermost ends of the strip members 25.

10 Said strips being rigidly retained against displacement at their opposite ends by the bracket arms 15. Stops 27 carried upon the inner faces of the spacing members are designed for abutting engagement with abbreviated jamb portions 28 formed as continuations of the door facing and upon the lower half thereof.

15

The latch mechanism, alluded to in the foregoing, comprises latch fingers 30 and 31 respectively vertically disposed in the manner shown in Figures 1 and 4 of the drawings and joined adjacent the innermost ends thereof through the instrumentality of a chain or linkage connection 32. The latch fingers are 20 slidably mounted within pockets or openings provided for the purpose in the cross braces 14. An ear 33 carried by the latch finger 30 is engaged upon one side thereof with the adjacent end convolution of a compression 25 spring 34 having its opposite end sprung against the upper side of the immediate of the cross braces 14 whereby the two latch fingers will be normally disposed in the positions shown in Figures 1 and 4. A latch plate 35 carried upon the upper rail of the door frame is provided with an opening designed for accommodation of the uppermost projecting end of the latch finger 30. An apertured ear 36 carried by and forwardly 30 projecting from the latch finger 31 through an opening 37 in the door 13 is designed for accommodation within the outer yoke receiving opening 38 in a form of hasp 39 swingably mounted upon the outer surface of the 35 door. The ear 36 being apertured for the purpose of accommodating the yoke of a lock, not shown. By removing the padlock from the ear 36, swinging the hasp 39 to occupy an elevated position and by depressing the ear 36, it is to be noted that the linkage connection 32 established between the adjacent extremities of the latch fingers 30 and 31 will facilitate releasing of the uppermost extremity of the latch finger 30 from the latch plate 35 even against the tension of the spring 34.

As shown the latch finger 30 and the door proper are each provided with separate pulls 40 and 41 respectively whereby the door may be readily unlatched from the inside and the door pulled bodily down from the Figure 3 position.

The invention is susceptible of various changes in its form, proportions and minor details of construction and the right is herein reserved to make such changes as properly

fall within the scope of the appended claim.

Having described the invention what is claimed is:

A vertically sliding door construction comprising complemental oppositely disposed bracket arms having vertically arranged elongated slots within the rearwardly projecting ends thereof, a beam terminally supported within said slots, a door, leg members carried by and depending from the rod having pintles inwardly projecting from the remaining extremities thereof for pivotal eccentric connections within diametrically opposite sides of the door, a fulcrum bar for the door, weight operated means carried by the bracket arms having operative connection with the projecting extremities of the fulcrum bar, and a latch mechanism for the door rendering inactive the leg members and weight operated means.

In testimony whereof I affix my signature.

FRANK B. DICKASON.
